UNITED STATES PATENT OFFICE.

FREDERICK H. PERRY, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ART OF GRINDING CUTTING EDGES.

1,400,767.

Specification of Letters Patent. Patented Dec. 20, 1921.

Application filed August 21, 1917. Serial No. 187,402.

To all whom it may concern:

Be it known that I, FREDERICK H. PERRY, of Beverly, in the county of Essex and State of Massachusetts, have invented certain Im-
5 provements in the Art of Grinding Cutting Edges, of which the following description, in connection with the accompanying drawings, is a specification, like reference characters on the drawings indicating like parts in the
10 several figures.

This invention relates to the sharpening or grinding of cutting edges and more particularly those of coöperating knives of different form such as are used, for example, in
15 jointing machines for trimming the edges of the shanks of shoes. In machines of this class there are, as fully explained in my Patent No. 1,030,605, dated June 25, 1912, a reciprocating trimming knife, having oppo-
20 site cutting edges, which operates upon the inner and outer edges of the shank portion of a shoe to give it the proper outline, and corresponding knives, called chopping knives, which reciprocate parallel to the breast of
25 the heel, serving to cut off the chips left by the trimming knife. As has been pointed out in the previously mentioned patent, the trimming and chopping knives, while different in form, must have one contour common
30 to both to enable the chopping knives to just sever the curved chips of the trimming knife without cutting into the shank. This common line lies along the edges of the trimming knife, as viewed longitudinally of the
35 body, and along the edges of the chopping knives, seen laterally. Obviously, if these edges are to cut to precisely the same points throughout their lengths, they must be so ground as to preserve always this identity of
40 contour.

An important object of this invention is the provision of an improved method whereby one of a plurality of coöperating knives may be so ground that in their use they will
45 cut along their entire edges, point for point, to a common line, and, moreover, that this relation shall be maintained as both knives are ground. This object is attained by employing a templet, for example, one of the
50 knives, to provide a guide for grinding another. Thus, in sharpening the knives of a jointing machine, the edge trimming knife may serve as a templet or in the formation of such a templet for the chopping knives.

The invention also provides novel apparatus by which my improved method may advantageously be carried into effect. In this a support for the knife or knives to be sharpened and a grinding surface, as the edge of a rotatable abrasive wheel, are movable relatively to subject the entire cutting edge to the grinding action, and the coöperating knife is utilized to determine the path of this feeding movement.

Since some machines, as the jointing machines previously referred to, employ two knives operating upon opposite sides of the work, it is desired to furnish means for quickly and conveniently arranging for the grinding of both knives. In the illustrated apparatus this is attained by using a single templet, as the trimming knife of the jointing machine, for grinding both the coöperating knives, this templet being movable, preferably by reversal, after one knife has been
65 ground to a position to adapt it for the grinding of the opposite knife. By suitable connections between the templet and knife support the preparation of the coöperating elements to grind the second knife may be
70 75 80 85 and as shown are made automatic.

Various other features are embraced by my invention as will be made evident by the following description and claims.

In the accompanying drawing—

Figure 1 is a side elevation of one embodiment of my improved apparatus, shown in position upon a portion of the frame of the machine to which it may be attached, the latter being in section;

Fig. 2 is a perspective view of the grinding apparatus;

Fig. 3 is a partial top plan view of the knife-holding and guiding elements, and

Fig. 4 is a detail perspective of a portion of the connections for shifting the stops.

Upon the frame 10 of a machine, the knives of which are to be ground, is secured a bracket 11 furnishing a support for the active elements of the apparatus of the present invention. This bracket carries a table 12 from which rises a standard 13 having journaled in it the shaft 14 of a suitable grinding wheel 15. Fast upon the grinding wheel shaft is a pulley 16 which may be driven by belt gearing from a shaft upon the machine to which the grinding apparatus is attached.

Depending from the under side of the table 12 are projections 17 having formed in their inner edges ways to receive a slide 18. At the rear of the slide 18 is a lug 19 in which is rotatably mounted a screw 20 threaded into an enlargement beneath the table. Carried upon the front face of the slide are blocks 21, 21 in alined bores in which is mounted a guide rod 22 having a limited longitudinal movement, as will hereinafter appear. Movable upon the rod are bearing members 23, 23 joined by a curved yoke 24 and carrying a supporting arm 25 which extends up through an opening 26 in the table 12. The arm 25 carries at its upper extremity a knife holder 27 in which are two vertical slots 28, 28 lying adjacent and parallel to one another and having at their tops pairs of ways 29, 29 to receive the shanks of the knives to be ground. A screw 30 passing through an opening in the holder below the ways and being threaded into the farther side serves to draw the ways together and thus gives a common means for clamping both knives in position. In the present instance, the chopping knives C and D which are to be ground have oppositely curved cutting edges *c* and *d* which enable them to work upon the right and left sides of the shoe shanks. These knives, when fixed in the ways in the holder, may be so positioned that their adjacent corners lie just at the opposite edges of the grinding surface of the wheel 15. To determine the length of the paths through which the knives are moved in their grinding, stops are provided consisting of screws 31, 31 threaded through arms 32, 32 secured to the ends of the guide rod 22. The knife holder is limited in its movement away from the grinding wheel as the arm 25 is turned about the rod 22 by contact of the arm with the outer edge of the opening 26 in the table 12, and may be swung therefrom to bring the edges of the knives C and D into contact with the wheel. To allow free inspection of the knives during their grinding the knife holder 27 is pivoted upon the arm 25 by means of a screw 33 and is locked in normal position by a spring-pressed pin 34 entering an opening in the face of the boss upon which the holder turns.

From one side of the arm 25 projects a branch arm 36 carrying a holder 37 in the form of a crank disk for the templet by which the chopping knives C and D are to be guided in the desired paths over the grinding wheel. In accordance with the illustrated embodiment of my invention, this templet is furnished by a trimming knife T which co-operates in the jointing machine with the chopping knives. At the outer edge of the crank disk is an angular portion provided in its inner face with dove-

tail ways 38 to receive the correspondingly formed portion of the trimming knife shank, the knife being secured in the ways by a clamping screw 39. At the rear of this templet is a guide-member furnished by the point of a screw 40 which is threaded through the upper end of an arm 41 secured to the front face of the slide 18. The end of the arm through which the screw 40 passes is slotted, the portions being drawn together by a screw 42 to fix the guide screw against rotation. The screw 40 is so adjusted through its arm with respect to the templet that when the latter is in contact with the point of the screw the knife holder will be moved sufficiently near to the edge of the grinding wheel to remove the desired amount of material from the knives C and D. As the support is slid longitudinally upon the rod 22 the engagement between the point of the guide screw and templet will cause the holder to describe a path exactly corresponding to said templet and therefore cause the chopping knife to be ground to the precise contour line of the trimming knife. The screw 20, previously described as co-operating with the lug upon the slide 18 enables the user of the apparatus to change the vertical position of the knives C and D with respect to the grinding wheel, thus permitting the use of wheels of different diameter. An adjustment of this screw, in connection with an alteration in the position of the guide screw 40, changes the angle at which the knives are presented to the grinding wheel and therefore the bevel at which they are ground.

To enable the operator to grind both knives with the same templet, the templet holder is preferably mounted upon a pivot pin 43 the axis of which is in alinement with the axis of the guide screw. Fast upon the pin 43 with the holder disk is an arm 44 carrying at its outer extremity a spring-pressed pin 45, which may enter a hole 46 at one end of a segmental surface at the top of the branch arm 36 or a corresponding hole at the opposite end of the segment with which the pin 45 is shown as in engagement in Fig. 2 of the drawings. When the pin 45 and the templet-holding disk are in their illustrated positions and the bearing member 23 is in contact with the left-hand stop screw 31, the knife holder will be so positioned that upon moving it toward the opposite stop screw the left-hand trimming knife C may be ground. Upon bringing the pin 45 into engagement with the hole 46 the position of the templet will be reversed, it now directing the guide screw 40 along its curved surface to the left instead of to the right to provide for the grinding of the other knife D having the opposite curvature. At the same time the

templet is reversed, the stops 31, 31 are preferably automatically adjusted to fix the limits of the path through which the particular knife to be ground is to move. Projecting 5 from the inner side of the holder disk 37 is a pin 47 having a ball head furnishing a universal connection for a rod 48, which at its other end is articulated upon a like pin 49 projecting from the upper arm 50 of a bell crank lever pivoted at 51 upon the slide 10. The lower arm 52 of the bell crank carries a pin 53 entering a circumferential groove 54 near the center of the rod 22. As the templet is reversed, as by moving the pin 15 45 from its illustrated position into engagement with the hole 46, the pin 47 on the templet-holding disk is moved from its uppermost to its lowermost position, causing the connecting rod 48 to swing down the arm 50 20 of the bell crank lever and carry the pin 53 to the right. This, engaging the slot 54, moves the rod 22 through the bearing members 23 so that the stop screws 31 are positioned to provide for a travel of the knife 25 support upon the rod from the right-hand contact screw to that at the left and fix the limits of the feeding movement of the knife D as was provided for in the case of the knife C with the stop pin 45 in engagement 30 with the opposite hole.

In the performance of my novel method by the use of the apparatus described both the chopping knives of a jointing machine are clamped in the holder 27 with their adjacent corners in the same transverse line and the trimming knife with which the chopping knives are to coöperate or a templet constructed therefrom is introduced into the holder 37. Then the apparatus is adjusted 35 by means of the screw 20 and the guide screw 40 to give the proper relation of the edges to be ground to the edge of the wheel and to produce the desired bevel. With the pin 45 in one of the holes in the segment, the support 45 25 is moved along the rod 22 between the stops to grind one of the knives. This having been accomplished, the trimming knife which is being used as the templet is reversed by carrying the pin 45 into the 50 other hole in the segment and the companion chopping knife similarly ground.

Having thus described my invention, what I claim as new and desire to secure by Letters Patent is:—

- 55 1. The method of sharpening upon an abrasive surface one of a plurality of curved knives having cutting edges of different form, which consists in supporting one knife in a grinding position, holding the other knife at an angle to the first, and moving the knives together to present the edge of the first knife to the abrasive surface while utilizing the transverse contour of the second knife as a guide.
- 60 2. The method of sharpening a pair of oppositely formed knives which in use co-operate with another knife to cut to common lines which consists in employing the last-named knife as a templet in grinding one of the pair of knives and then reversing the templet in grinding the other knife of the pair.
- 65 3. In an apparatus for grinding one of a plurality of coöperating knives, a grinding member, a support for one of the coöperating knives, said member and support being relatively movable to permit the feed of these elements by one another, means including a guide in the form of another of said knives for determining the path along which this feeding movement shall occur, and means controlled by the guide by which the length of said path may be variably determined.
- 70 4. In an apparatus for grinding one of a plurality of coöperating knives of different form, a grinding member, a support for one of the coöperating knives, said member and support being relatively movable to permit the feed of these elements by one another, a second support for holding the other of the coöperating knives in a plane substantially perpendicular to the plane of the first-mentioned knife, whereby said feeding movement follows a path corresponding with the profile of the last-mentioned knife, and means for mounting the supports for angular movement with respect to the grinding member.
- 75 5. In an apparatus for grinding one of a plurality of coöperating knives of different form, a grinding member, a support for one of the coöperating knives, said member and support being relatively movable to permit the feed of these elements by one another, a second support for holding the other of the coöperating knives in a plane substantially perpendicular to the plane of the first-mentioned knife, whereby said feeding movement follows a path corresponding with the profile of the last-mentioned knife, and means for holding said path-determining knife in a plurality of positions to adapt it for grinding different knives.
- 80 6. In an apparatus for grinding one of a plurality of coöperating knives, a grinding member, a support for one of the coöperating knives, said member and support being relatively movable to permit the feed of these elements by one another, means including another of said knives for determining the path along which this feeding movement shall occur, means for holding said path-determining knife in a plurality of positions to adapt it for grinding different knives, and means controlled by the position of the path-determining means for presenting different knives to the grinding member.
- 85 7. In an apparatus for grinding one of a plurality of coöperating knives, a grinding member, a support for one of the coöperating knives, said member and support being relatively movable to permit the feed of these elements by one another, means including another of said knives for determining the path along which this feeding movement shall occur, means for holding said path-determining knife in a plurality of positions to adapt it for grinding different knives, and means controlled by the position of the path-determining means for presenting different knives to the grinding member.

ing knives, said member and support being relatively movable to permit the feed of these elements by one another, means including the transverse side face of another of said knives for determining the path along which this feeding movement shall occur, and means for holding said path-determining knife in reverse positions to adapt it for grinding oppositely formed knives.

10 8. In an apparatus for grinding one of a plurality of coöperating knives, a grinding member, a support for one of the coöperating knives, said member and support being relatively movable to permit the feed of these elements by one another, means including another of said knives for determining the path along which this feeding movement shall occur, means for holding said path-determining knife in reverse positions to adapt it for grinding oppositely formed knives, and means controlled by the position of the path-determining means for presenting one or the other of the knives to the grinding member.

15 9. In an apparatus for grinding one of a plurality of differently formed coöperating knives adapted for different cutting operations, a grinding member, a support for the knife to be ground, said member and support being relatively movable to permit the feed of these elements by one another, a holder constructed and arranged to receive one of the differently operating knives and support it in a plane substantially perpendicular to the plane of the knife to be ground, and means coöperating with the last-named knife to guide the feeding movement.

20 10. In an apparatus for grinding one of a plurality of differently formed coöperating knives adapted for different cutting operations, a grinding member, a support for the knife to be ground, said member and support being relatively movable to permit the feed of these elements by one another, a holder constructed and arranged to receive one of the differently operating knives and support it in a plane substantially perpendicular to the plane of the knife to be ground, and means coöperating with the last-named knife to guide the feeding movement, said means and guide knife being relatively adjustable toward and from one another.

25 11. In an apparatus for grinding the chopping knives of machines for operating upon the shanks of shoes by trimming knives, a grinding wheel, a support for the chopping knife and a reversible support for a shank-trimming knife movable together, and a member coöperating with the trimming knife for guiding the chopping knife over the wheel.

30 12. The combination with a grinding wheel, of a support provided with means for mounting thereon a plurality of knives to be ground, a movable templet, guiding means

contacting with the transverse surface or profile of the templet, and means operable in the movement of the templet for presenting different knives to the grinding wheel.

35 13. The combination with a grinding wheel, of a support provided with means for simultaneously holding thereon a plurality of oppositely formed knives to be ground, a reversible templet, guiding means contacting with the templet and means to guide the support in one direction to start the grinding of one blade and to guide the support in the opposite direction to start the grinding of the oppositely formed blade.

40 14. The combination with a grinding wheel, of a movable support provided with means for clamping thereon knives to be ground, a templet holder movable upon the support, a guide for coöperation with the templet, a stop for the support, and connections operable in moving the templet for changing the position of the stop.

45 15. The combination with a grinding wheel, of a support provided with means for clamping thereon oppositely formed knives to be ground, a templet holder pivoted upon the support, a guide point situated in alignment with the pivotal axis of the templet holder, and connections operable in swinging the templet about its pivot for changing the relation of the knives to the grinding wheel.

50 16. In a grinding apparatus, the combination with a frame, of a grinding wheel rotatable thereon, a support movable in the frame and being provided with means for clamping thereon oppositely formed knives to be ground, a movable stop for the support, a templet holder pivoted upon the support, a guide for coöperation with the templet, a lever fulcrumed upon the frame, connections between the templet holder and lever, and means coöperating with the lever to rock it in the movement of the holder to move the stop and thereby adapt the apparatus for grinding the knife other than that previously ground.

55 17. In a grinding apparatus, the combination with a frame, of a grinding wheel rotatable thereon, a movable support, a guide rod therefor, a knife holder situated adjacent to the grinding wheel and being pivoted upon the support, means for fixing the knife holder in different angular positions with respect to the grinding wheel, a templet holder carried by the support, and a guide for coöperation with the templet.

60 18. In a grinding apparatus the combination with a frame, of a grinding wheel rotatable thereon, a movable support, a holder provided with pairs of grooves, means common to the pairs of grooves for clamping two knives to be ground, a templet usable in grinding either knife, and a guide member for coöperation with the templet.

19. In a grinding apparatus, the combination with a frame, of a grinding wheel rotatable thereon, a movable support, a guide rod therefor, stops carried by the guide rod 5 at opposite sides of the support, a knife holder and a templet holder carried by the support, and a guide member for contact with the templet.
20. In a grinding apparatus, the combination with a frame, of a grinding wheel rotatable thereon, a guide rod provided with 10 a groove, a stop carried by the guide rod, a support movable along the guide rod, a knife holder fixed to the support, a templet holder pivoted upon the support, a lever fulcrumed on the frame and having a projection engaging the groove in the guide rod, connections between the lever and templet 15 holder, a guide member for contact with the templet, and means for fixing the templet in either of two extreme positions.
21. In a grinding apparatus, the combination with a frame, of a grinding wheel ro- 20
- tatable thereon, a guide rod provided with a groove, a stop carried by the guide rod, a support movable along the guide rod, a knife holder fixed to the support, a templet holder pivoted upon the support, a lever fulcrumed on the frame and having a projection engaging the groove in the guide rod, connections between the lever and templet holder, a guide member for contact with the templet, and means for fixing the templet in either of two extreme positions.
22. The combination with a grinding wheel, of a support provided with means for mounting thereon a plurality of knives for operating at different angles, and means for varying the position of the support with relation to the grinding wheel to correspond to the operating positions of the knives. 35
- In testimony whereof I have signed my name to this specification. 40

FREDERICK H. PERRY.
